Specification for Design.

Patented Mar. 7, 1922.

Application filed February 12, 1921. Serial No. 444,620. Term of patent 14 years.

To all whom it may concern:

Be it known that we, EARL S. R. BICKEL and PENN DE BARTHE, citizens of the United States, residing in the city of Philadelphia, county of Philadelphia, and State of Pennsylvania, have invented a new, original, and ornamental Design for a Badge, Pin, Button, or Similar Emblem, of which the following is a specification, reference being had to the accompanying drawing, forming a part thereof.

The figure is a front view of a badge, pin, button or similar emblem showing our new design.

We claim:

The ornamental design for a badge, pin, button, or similar emblem as shown.

In testimony whereof we have hereunto set our names this tenth day of February, 1921.

EARL S. R. BICKEL.
PENN DE BARTHE.
